Her ATTORNEY.*

UNITED STATES PATENT OFFICE.

AMELIA I. ROONEY, OF PITTSBURGH, PENNSYLVANIA.

LID-LOOSENER.

1,187,785.

Specification of Letters Patent. Patented June 20, 1916.

Application filed September 30, 1915. Serial No. 53,271.

To all whom it may concern:

Be it known that I, AMELIA I. ROONEY, a citizen of the United States, and residing in the city of Pittsburgh, in the county 5 of Allegheny and State of Pennsylvania, have invented or discovered new and useful Improvements in Lid-Looseners, of which the following is a specification.

My invention consists of a new and improved device for loosening the lids of metal boxes and other containers.

My improved loosener is particularly adapted for use in connection with boxes provided with lids having depending edge 15 flanges fitting down over the outside wall of the box.

My loosener is separate from both box and lid and, when the lid is put in place, is interposed between the box and the lid.

20 The lid is loosened by tilting the loosener, resulting in forcing the lid upwardly away from the box.

In applying my invention to boxes containing such substances, as shoe-polish, 25 which are applied by means of a dauber, I provide the inner end of my loosener with a dauber-brush.

In the accompanying drawings, Figure 1 is a perspective of an open blacking box 30 showing the loosener in place for the application of the lid to the box; Fig. 2 is a diametric section of the box and lid, showing the loosener mounted in its place; Fig. 3 is a front elevation showing the lid loosened 35 from the box by the tilting of the loosener, and Fig. 4 is a perspective of the loosener with the dauber feature omitted.

The following is a detailed description of the drawings, reference being first had to 40 Figs. 1, 2 and 3, wherein A is the box, and B is the lid for the same, provided with a depending edge flange 1 which fits down over the box A in the usual manner. C is the loosener, stamped into shape from stiff 45 sheet metal. Said loosener is composed of a laterally winged portion 2 curved to fit the contour of the upper edge of the box A; a reduced, depending neck portion 3, and an outwardly extending grip 4. Where 50 the loosener is to be used as a dauber when the box is open, I provide the loosener with an extension at its inner end upon which is mounted the dauber brush 5.

When the lid is in place, the dauber brush 55 is contained within the box, as shown in the drawings, the winged portion 2 is held

between the top edge of the box and the under face of the lid, and the neck 3 extends downwardly between the flange 1 and the outside of the box. The loosener, being 60 formed of thin metal, does not appreciably interfere with the air-tight character of the box when the lid is in place.

To loosen the lid, the grip 4 is seized by the fingers and swung to one side or other 65 out of the vertical, thus tilting the winged portion 2. The tilting of said winged portion, as shown in Fig. 3, results in its lower extremity bearing against the top edge of the box while its upper extremity bears 70 against the under surface of the lid, raising the latter, as shown so that it falls or may be lifted from the box. Owing to the leverage furnished by the neck 3, but little force is required to lift the tightest lid. 75

When formed as a dauber, a convenient and cleanly method of storing the dauber, when not in use, is provided, and the dauber does not become dried out and hardened.

My loosener is inexpensive, so as not to 80 appreciably add to the cost of boxed goods. Where the dauber feature is omitted, as in Fig. 4, the device is applicable to any character of boxed or canned goods where a flanged lid is used. 85

What I desire to claim is:—

1. In combination with a container and a lid for the same provided with a depending edge flange which fits down over the upper wall of said container, of a loosener for said lid stamped integrally of metal and comprising an outwardly extending handle, a relatively narrow neck extending up between said lid flange and the wall of the container; and a laterally winged body portion of the proper contour to fit between the top edge of the container and the under face of the lid proper whereby, when said handle portion is swung to one side out of its normal vertical position, one wing of said body portion bears against the top edge of the container while the opposite wing of said body portion bears against the under face of the lid, thus wedging said lid loose from said 95 container, substantially as and for the purpose described. 100

2. In combination with a container and a lid for the same provided with a depending edge flange which fits down over the upper wall of said container, of a loosener for said lid stamped integrally of metal and 110

comprising an outwardly extending handle, a relatively narrow neck extending up between said lid flange and the wall of the container, a laterally winged body portion 5 of the proper contour to fit between the top edge of the container and the under face of the lid proper whereby, when said handle portion is swung to one side out of its normal vertical position, one wing of said body 10 portion bears against the top edge of the

container while the opposite wing of said body portion bears against the under face of the lid, thus wedging said lid loose from said container, and a dauber integral with said body portion and extending inwardly 15 therefrom beneath said lid, substantially as and for the purposes described.

Signed at Pittsburgh, Penna., this 29th day of September, 1915.

AMELIA I. ROONEY.
